UNITED STATES PATENT OFFICE.

WILLIAM HENRY JAY, OF LE BEAU, SOUTH DAKOTA.

FIRE-ESCAPE.

No. 927,148.

Specification of Letters Patent.

Patented July 6, 1909.

Application filed December 29, 1908. Serial No. 469,842.

To all whom it may concern:

Be it known that I, WILLIAM HENRY JAY, a citizen of the United States, and a resident of Le Beau, in the county of Walworth and 5 State of South Dakota, have invented a new and Improved Fire-Escape, of which the following is a full, clear, and exact description.

My invention relates to fire escapes, and it 10 has for its object to provide a standard which will permit a person to embrace it and slide to the ground, there being means to enable the person to regulate the rapidity of his descent, without burning or chafing his 15 hands or other portions of his body.

Still other objects will appear in the following complete description.

In this specification I will describe the preferred form of my invention, but it will 20 be understood that I do not limit myself thereto, as I consider myself entitled to all forms and embodiments of the invention which may be held to fall within the scope of the appended claims.

Reference is to be had to the accompanying drawings, forming a part of this specification, in which similar characters of reference indicate corresponding parts in all the figures, in which—

Figure 1 is an elevation of a building with my fire-escape in position relatively thereto; Fig. 2 is an elevation of my fire escape, parts being shown in section to illustrate its operation; Fig. 3 is a sectional view looking downwardly, on the line 4—4 of Fig. 2; Fig. 4 is a sectional view looking upwardly, on the line 4—4 of Fig. 2; and Fig. 5 is a sectional view on the line 5—5 of Fig. 2, looking upwardly.

By referring to the drawings, it will be seen that a hollow standard 1 is disposed perpendicularly in front of a building 2, the standard 1 being secured to heads 3, which are in turn bolted to brackets 4, the brackets 4 being bolted to the front of the building, the lower one being also bolted to the sidewalk, if desired. The standard 1 opens into the heads 3, each of which has openings 5 therein, in which are journaled 50 pulleys 6, continuous belts 7 being mounted on these pulleys 6, the continuous belts 7 extending in one direction within the hollow standard 1 over the top pulley and then without the standard to the lower pulley 55 over which it is disposed. I propose to

mount four or more of these belts 7, which are disposed to travel longitudinally of the hollow standard 1, and to hold these belts 7 in close proximity to the hollow standard 1, I provide collars 8 which are bolted to the hollow standard 1 and have openings 9 therein, in which are journaled pulleys 10, the pulleys 10 being so disposed that they will press against the continuous belts 7 to hold them close to the hollow standard. 60 One of these collars 8 is secured to the hollow standard just below the upper head 3, and the other collar 8 is secured to the standard near its base. 65

In the operation of my invention, when 70 a person desires to descend on the fire escape, he embraces the device which is disposed in close proximity to a window or door, and slides down to the ground. In his descent his hands and arms encircle the standard, 75 but inasmuch as the continuous belts 7 are disposed around the outer sides of the standards, his arms and hands come in contact with said belts, which prevent his hands and other portions of his body from becoming 80 burned or chafed by frictional contact with the hollow standard. At the same time it is possible for the person to regulate the rapidity of his descent, for by pressing the continuous belts against the hollow standard, 85 he can by frictional contact of the belts with the standard, slide to the ground as slowly as he may desire, the continuous belts 7 during his movement traveling with his body, so that he is not injured in any way by 90 frictional contact.

In using my invention, it may be found to be advisable to erect a plurality of standards at different levels so that the user may slide down one standard to a platform from 95 which he may go to a second standard to continue his descent.

Having thus described my invention, I claim as new and desire to secure by Letters Patent:

1. In a fire escape, a standard of such a size in cross section as will permit it to be grasped by the user, and belts disposed around the standard to travel longitudinally thereof and form a movable cover for the 105 outer surface of the standard.

2. In a fire escape, a standard of such a size in cross section as will permit it to be grasped by the user, belts disposed around the standard to travel longitudinally thereof 110

and form a movable cover for the outer surface of the standard, and means for holding the belts close to the standard.

3. In a fire escape, a hollow standard of such a size in cross section as will permit it to be grasped by the user, and a continuous belt disposed to travel within and without the standard, the belt forming a longitudinally movable cover for the outer surface of the hollow standard.

4. In a fire escape, a standard of such a size in cross section as will permit it to be readily grasped by the user, pulleys journaled therein at a distance from each other longitudinally of the standard, and a belt disposed on the pulleys in close proximity to the standard, the belt forming a longitudinally movable cover for the outer surface of the standard.

5. In a fire escape, a hollow standard with openings therein, the hollow standard being of such a size in cross section as will permit it to be grasped readily by the user, the openings being at a distance from each other longitudinally of the hollow standard, pulleys journaled in the openings, and continuous belts disposed on the pulleys to travel within and without the hollow standard, the belts forming a longitudinally movable

cover for the outer surface of the hollow standard.

6. In a fire escape, a standard of such a size in cross section as will permit it to be readily grasped by the user, pulleys journaled at a distance from each other longitudinally of the standard, belts disposed on the pulleys, the belts forming a longitudinally movable cover for the outer surface of the standard, and means for holding the belts close to the standard.

7. In a fire escape, a standard of such a size in cross section as will permit it to be readily grasped by the user, pulleys journaled at a distance from each other longitudinally of the standard, belts disposed on the pulleys, a collar disposed around the standard, and pulleys journaled in the collar, which are adapted for holding the belts in close proximity to the standard, the belts forming a longitudinally movable cover for the outer surface of the standard.

In testimony whereof I have signed my name to this specification in the presence of two subscribing witnesses.

WILLIAM HENRY JAY.
